UNITED STATES PATENT OFFICE

2,425,716

ELECTROMAGNETIC HORN

Wilmer Lanier Barrow, Newton, Mass., assignor
to Research Corporation, New York, N. Y., a
corporation of New York

Application July 24, 1937, Serial No. 155,489

4 Claims. (Cl. 250—11)

1

The present invention relates to electric communication.

The invention will be described more fully in connection with the accompanying drawing, the single figure of which is a diagrammatic view of circuits and apparatus embodying the present invention, showing, in longitudinal section, an electromagnetic horn connected to a coaxial pipe.

An electromagnetic horn 88, of circular or annular flared-out conformation, is shown at the free open end of an elongated tubular or pipe body portion or section 94, that may extend over any desired distance from the small end or throat of the horn. The horn may be constituted of metal, such as copper or aluminum, or it may be constituted of other material if its inner wall is otherwise rendered a conductor of the waves. The electromagnetic horn is provided with a guiding surface or guiding walls that connect the small end or the throat and the large end or the mouth of the horn. The horn thus operates to guide waves traveling within it and tangentially along its surface in the longitudinal direction, smoothly and without interruption. In reception, electromagnetic waves received from space at the mouth of the horn are guided to the throat end of the horn. In transmission, electromagnetic waves generated at the small end of the horn are directed forward out into space.

The pipe 94 constitutes the outer tubular conductor of a coaxial-cable or coaxial-line or coaxial-feed transmitting system 92, 94, the extended inner or central conductor 92 of which may be supported substantially centrally in, and spaced from the walls of, the tube 94, largely along the axis of the pipe 94 and the horn 88, by insulating members (not shown). The central conductor 92 extends inside the tubular member 94, 88, and into the throat of the horn 88, where it terminates, to provide therein a free terminal beyond which the conductor 92 does not extend. The portion of the conductor 92 in the neighborhood of the free terminal is shown departing somewhat from the said axis. This free terminal is continuously joined to one end of an exciting or absorbing loop antenna rod 87, the other end 90 of which is shown connected to the horn 88. The rod 87 is illustrated as disposed in a plane through, and substantially at right angles to, the said axis. It is shown positioned approximately centrally directly in the throat of the horn, outwardly of any portion of the horn, such as the pipe 94, that may be of substantially uniform cross section.

2

The rod 87 thus constitutes a connecting conductor, disposed inside the tubular member 88, 94, for connecting the said free terminal of the conductor 92 to the tubular member 94, thus to provide a continuous conducting path for carrying current between the tubular member 94 and the conductor 92 of the coaxial line. This construction enables the rod 87 to excite or intercept electromagnetic waves.

10 To this end, the rod 87 may be connected to terminal apparatus, as by means of two-wire connecting leads 10 and 12. One of the leads, as the wire 10, may be connected to the outer tubular conductor 94, and the other lead, as the wire 12, to the central conductor 92 of the coaxial-feed line. The terminal apparatus may be connected to sending or receiving apparatus, at a sending or receiving station. For sending, the leads 10 and 12 may be connected to means for energizing the 20 antenna 87. For receiving, they may be connected to means for evidencing the received waves absorbed by the antenna 87.

The horn is shown connected to a transmitting system comprising a radio-frequency oscillator 2, 25 provided with a modulator 3, which may be modulated in any desired way, as by means of a microphone 4. The modulated output may be fed to a radio-frequency amplifier 6 that may be coupled to a circuit 8 having the leads 10 and 12 in its 30 output circuit. The described means of connecting the horn 88 to the coaxial line 92, 94 provides an exciting rod 87 substantially transverse to the axis of the pipe and the horn for beam transmission. The modulated ultra-high-frequency energy may be taken by the conductors 10 and 12 from the sending apparatus and delivered to the antenna 87 in the small end of the horn. Current waves in the antenna 87 become impressed from the central conductor 92 upon the 40 rod 87. The antenna 87 will excite modulated ultra-high-frequency electromagnetic waves of horn type, or "horn waves," near the small end of the horn. The waves will be transversely polarized, that is, the electric intensity will be entirely in surfaces normal to the direction of propagation. These transversely polarized waves will be propagated through the interior of the horn toward the large end or the mouth thereof, and finally beyond the mouth of the horn, into free space, as ordinary radio waves. A beam will be radiated from the horn mouth of character appropriate to the horn itself, rather than to the antenna 87 and the other apparatus. 45 50 55 Similar but reverse operation will take place

for reception of the waves, the large end or the mouth of the horn being electromagnetically open to space to permit the horn to receive electromagnetic waves from space. Modulated ultra-high-frequency electromagnetic waves, received at the mouth of the horn, will be communicated to the antenna 87, by which they will be absorbed, after which the energy will be conducted down the horn and the pipe to be delivered to the receiving apparatus (not shown), where the signal comprising the intelligence will be recovered by demodulation.

A coaxial-type wave transmitted along the tubular member 94 and the conductor 92 disposed therein, therefore, will be converted into a transverse-electric-type wave in the tubular member 94 beyond the connecting conductor 87; or vice versa, a transverse-electric-type wave in the tubular member beyond the connecting conductor 87 may be converted into a coaxial-type wave transmitted along the tubular member and the conductor 92 disposed therein. The waves will not be more fully described herein because they will be understood without further description by reference to a paper by L. J. Chu and W. L. Barrow, entitled, "Electromagnetic waves in hollow metal tubes of rectangular cross section," proceedings of the Institute of Radio Engineers, vol. 26, No. 12, December, 1938, commencing at page 1520, and also to a paper by Barrow, entitled, "Electromagnetic-horn radiators," Union Radio Scientifique Internationale, No. 79, p. 277, containing a revision of a paper presented at the Joint Meeting of the said Union and the Institute of Radio Engineers, at Washington, D. C., April 30, 1938. See also a paper by W. L. Barrow and L. J. Chu, entitled, "Theory of the electromagnetic horn," Proceedings of the Institute of Radio Engineers, vol. 27, No. 1, January, 1939, commencing at page 51, and also a paper by W. L. Barrow and F. D. Lewis, entitled, "The sectoral electromagnetic horn," Proceedings of the Institute of Radio Engineers, vol. 27, No. 1, January, 1939, commencing at page 41.

The invention is not limited to the exact embodiment thereof that is illustrated and described herein. Modifications may be made by persons skilled in the art without departing from the spirit and scope of the invention, as defined in the appended claims.

What is claimed is:

1. An electric system having, in combination, an electromagnetic-wave-guide horn having a small end and a large end, the large end being electromagnetically open to space to permit the horn to receive electromagnetic waves from space or to radiate electromagnetic waves out into space at the large end, absorbing or exciting antenna means disposed in the horn at the small end, the horn having guiding walls between the large end and the small end for guiding the waves received from space at the large end to the antenna means at the small end in order that the received waves may be absorbed by the antenna means or for guiding to the large end for radiation out into space the waves excited by the antenna means at the small end, coaxial-line means for connecting the antenna means with means for evidencing the received waves absorbed by the antenna means or with means for energizing the antenna means to excite at the small end the waves to be radiated out into space, the coaxial-line means having a substantially centrally disposed conductor connected to the antenna means and an outer tubular conductor

connected to the horn, and means for connecting the antenna means to the outer tubular conductor.

2. An electric system having, in combination, 5 an electromagnetic-wave-guide horn having a small end and a large end, the large end being electromagnetically open to space to permit the horn to receive electromagnetic waves from space or to radiate electromagnetic waves out into space at the large end, absorbing or exciting 10 antenna loop means disposed in the horn at the small end, the horn having guiding walls between the large end and the small end for guiding the waves received from space at the large end to the antenna means at the small end in order that the received waves may be absorbed by the antenna means or for guiding to the large end for radiation out into space the waves excited by the antenna means at the small end, coaxial-line means 15 for connecting the antenna means with means for evidencing the received waves absorbed by the antenna means or with means for energizing the antenna means to excite at the small end the waves to be radiated out into space, the coaxial-line means having a substantially centrally disposed conductor connected to one portion of the loop means and an outer tubular conductor connected to the horn, and means for connecting another portion of the loop means to the outer tubular conductor.
3. An electric system having, in combination, 20 an absorber or radiator for receiving electromagnetic waves from space or radiating electromagnetic waves out into space, absorbing or exciting 25 antenna means disposed in the absorber or radiator, coaxial-line means for connecting the antenna means with means for evidencing the received waves absorbed by the antenna means or with means for energizing the antenna means to 30 excite the waves to be radiated out into space, the coaxial-line means having a substantially centrally disposed conductor connected to the antenna means and an outer tubular conductor connected to the absorber or radiator, and means 35 for connecting the antenna means to the outer tubular conductor.

4. A conductor of electromagnetic waves having, in combination, a coaxial line comprising a 40 conducting tubular member and a conductor disposed substantially centrally of the tubular member and terminating inside the tubular member to provide in the tubular member a free terminal beyond which the conductor does not extend, and means comprising a connecting conductor in the 45 tubular member connecting the free terminal to the tubular member and carrying current between the tubular member and the conductor disposed therein to convert a coaxial-type wave transmitted along the tubular member and the 50 conductor disposed therein into a transverse-electric-type wave in the tubular member beyond the connecting conductor, or to convert a transverse-electric-type wave in the tubular member beyond the connecting conductor into a coaxial-type wave transmitted along the tubular member and the conductor disposed therein.

WILMER L. BARROW.
